UNITED STATES PATENT OFFICE.

OMAR C. MOTE, OF WEST MILTON, OHIO.

DEVICE FOR HANGING TOBACCO.

SPECIFICATION forming part of Letters Patent No. 629,267, dated July 18, 1899.

Application filed February 10, 1899. Serial No. 705,185. (No model.)

To all whom it may concern:

Be it known that I, OMAR C. MOTE, a citizen of the United States, residing at West Milton, in the county of Miami and State of Ohio, have invented certain new and useful Improvements in Devices for Hanging Tobacco; and I do hereby declare the following to be a full, clear, and exact description of the invention, such as will enable others skilled in the art to which it appertains to make and use the same.

This invention relates to a device for hanging tobacco; and the purpose of the same is to facilitate placing tobacco in a shed, and avoid the danger of climbing up into the latter and in addition to conveniently accomplishing the said desired result to utilize means therefor which are strong and durable, efficient in operation, easily handled, and comparatively inexpensive.

The invention consists of the construction and arrangement of parts hereinafter more fully described and claimed.

In the accompanying drawings, Figure 1 is a perspective view of the improved device, showing the parts in operative position. Fig. 2 is a perspective view of the extensible sections of the device reduced to compact form, the supplemental hanger being omitted. Fig. 3 is a section on the line *x x*, Fig. 1. Fig. 4 is a section on the line *y y*, Fig. 1. Fig. 5 is a detail perspective view of one of the standards and one of the cross-strips.

Referring to the drawings, wherein similar numerals are employed to indicate corresponding parts in the several views, the numeral 1 designates opposite side track-rails connected at opposite ends by cross-tie strips 2, and at the corners casters 3 are attached for convenience in moving this base-frame as may be desired and found necessary during the operation for which the device is designed. On this base-frame a horizontal support 4 is movably mounted and consists of top cross-strips 5, spaced apart from each other and parallel, and lower similar strips 6, directly under the said first-mentioned strips 5. Between the said strips 5 and 6 the lower ends of opposite standards 7 are rigidly located inward from the rails 1, and parallel with the said rails between the strips 5 and 6

and adjacent the outer sides of standards are blocks 8, one on each side, having in their outer edges lash or trunk rollers 9, that bear against the inner edges of the rails. The under portions of the strips 5, located over the rails, and the similar upper portions of the strips 6 have rollers 9 secured thereto, moving on opposite sides of said rails, and by this means the support 4 has a very sensitive anti-frictional adjustment on the base-frame.

The opposite edges of the lower portions of the standards 7 are formed with adjacent mortises 10, and the inner edges of the strips 5 and 6 are likewise provided with mortises 11 near opposite ends, and the mortises in the said parts are brought together and a substantial jointure thereby attained. The said standards are connected above the support 4 by tie-bolts 12 at different elevations therein, and held firmly in engagement with said standards by said bolts is a lower ladder-section 13, comprising opposite rails 14, united by rounds 15. Adjustably fitted in said lower ladder-section 13 is a second ladder-section 16, of less width than the first section and having rails 17 and rounds 18. The rails 17 are slidingly attached to the rails 14 by guides 19, and in like manner a third ladder-section 20 is applied to the section 16. The said third section has rails 21, movably held in engagement with the rails 17 by guides 22 and provided with rounds 23. These ladder-sections in part are controlled as to their adjustment by a rope 24, which is first passed through a pulley 25 on the central part of the uppermost round of the first section, then down and through a pulley 26 on the lowermost round of the second section, then up through a pulley 27 on the uppermost round of said second section, and down to the lowermost round of the third section, where it is attached by a hook 28 on the upper termination thereof. By pulling this rope the second and third sections will be projected upwardly in succession and held extended by making the said rope fast to one of the tie rods or bolts 12 below. By loosening and slackening said rope the ladder-sections will slide downwardly by gravitation.

On the topmost round 23 of the third ladder-section 20 an elevating-frame 28^a is con-

ected and comprises two strips 29, supported by said round and located just inside and against the rails 21 of said section. The outer portions of said strips 29 are connected by a round 30, and secured to the under edges of the inner parts of the strips are brace-stops 31, which bear against the adjacent edges of the said rails 21, and thereby sustain the elevating-frame in a horizontal position relatively to the said ladder-section holding the same. This elevating-frame is arranged to project over the side of the ladder-sections opposite that on which the lower ends of the sections are exposed in order to avoid tearing or injuring the tobacco when raised, which might result if drawn up on the side where said ends form projecting angles.

To the round 30 three pulleys 32, 33, and 34 are attached, the pulley 33 being located at the center and the two others at the opposite ends. Through these pulleys three ropes 35, 36, and 37 are passed, the central rope 36 being secured at one end to a central eye 38 of a common form of tobacco-hoisting bail or hook 39 and having hooks 40 at its ends, to which are attached the two other ropes 35 and 37. These latter ropes 35 and 37 are crossed and passed through the eye 38, and the object of this is to raise either end of the stick being elevated higher than the other, and, further, a sidewise movement to the stick can also be imparted, said movements being regulated by the tension exerted on the said ropes 35 and 37. The opposite ends of the ropes 35, 36, and 37 are carried over the topmost round of the third ladder-section and made long enough to drop near to the ground or within convenient reaching distance, and to prevent entanglement of the lower ends and consequent confusion in the operation of the same they are fastened separately to a lower part of the device. The ends of the ropes 35 and 37 are secured in eyes 41, formed as a part of hooks 40, to overcome any tendency toward slipping. A supplemental hanger attachment is also adapted to be held on the upper or third ladder-section, as shown by Fig. 1, and purposely left off, Fig. 2, to avoid confusion, and which will be used at various times, and to provide means for mounting this device the two uppermost rounds of said ladder-section are projected laterally on one side, as at 42 and 43. To the projected portion 42 the lower end of a vertical member 44 of said attachment is pivotally mounted and from the outer portion thereof has a horizontal member 45 extending transversely therefrom. To the projecting portion 43 a pulley 46 is secured, through which a rope 47 is passed and attached to the horizontal member 45 by a hook 47^a, both ends of said rope dropping equally to a point near the ground for providing means to move the supplemental hanger attachment backward and forward.

65 The member 44 has a series of openings 48 for the purpose of adjusting the entire sup-

plemental hanger attachment, as may be desired. This attachment is intended to carry tobacco away from the uppermost ladder-section and when the entire device cannot be pushed back any farther, as in finishing a rail, and a stick is immediately under. In this event the ladder-sections will be lowered temporarily and afterward raised. This attachment need not be used except in finishing a rail and is generally folded up against the ladder-section supporting it. It is worked or operated by the rope 47, and when the last stick hung interferes with further operation of hanging said attachment is moved to bear against the said last stick to push its leaves out of the way and assist in positioning a stick above the place where the device has been standing.

To operate the machine, ordinarily the rails 85 are spaced and each tier hung beginning at the top. The base-frame is positioned under the rail desired to be hung and beginning, for example, at one end of the shed. A stick is then placed in the bail and run up above the rail and at the same time shoving the support 4 as near the end of shed as possible. The stick is then lowered in place, and simultaneously said support is shifted forwardly sufficiently to position the next stick and without touching the one just hung. The support 4 is moved by the foot of the operator, thereby leaving the hands free to manipulate the ropes connected to the various parts. This operation continues throughout the length of a rail and the end finished up by the supplemental hanger attachment. The base-frame can then be moved easily and quickly under another rail for a similar operation.

The parts of the device when not in use can be quickly reduced into comparatively compact form for storage or other purposes, and changes in the proportions or dimensions can be made to suit different sheds or for other purposes. The device has many advantages and will save labor, time, and expense in hanging tobacco and avoid the danger incident to climbing up into the shed.

Having thus described the invention, what is claimed as new is—

1. In a tobacco-hanging device, the combination of a series of adjustable ladder-sections, an elevating-frame adjustably carried by one of said sections, a tobacco-elevating bail, and means for operating said parts.
2. In a tobacco-hanging device, the combination of a series of adjustable ladder-sections, an elevating-bail, a freely-movable support for said sections, and means for operating said parts.
3. In a tobacco-hanging device, the combination of a series of adjustable ladder-sections, an elevating-bail, a freely-movable support for said sections, a base-frame on which said support moves, and means for operating said parts.
4. In a tobacco-hanging device, the combi-

nation of a series of extensible sections, a tobacco - elevating bail, an upper elevating-frame, an adjacent supplemental hanger attachment, and a lower freely-adjustable support for said sections.

5. In a tobacco-hanging device, the combination of extensible sections, a bail, three ropes attached to said bail, one at the center and two crossed and connected to opposite portions thereof, means for supporting said sections, and means for operating the several devices.

6. In a tobacco-hanging device, the combination of a base-frame comprising side rails, a support having opposite upper and lower strips and intermediate blocks all supplied with rollers bearing on the said rails, extensible sections held on said support, a bail, and

means for raising and lowering said bail on the sections.

7. In a tobacco-hanging device, the combination of a base-frame, a support movable thereon comprising opposite pairs of strips with mortises in the inner edges, standards having mortises in the outer edges to fit the mortises of the strips, ladder-sections adjustably held by said standards, and means for raising and placing tobacco-sticks held by the said sections.

In testimony whereof I affix my signature in presence of two witnesses.
